(57) **CLAIM**

The ornamental design for a data cable, as shown and described.

DESCRIPTION

FIG. 1 is a first perspective view of a first embodiment of a data cable showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a first perspective view of a second embodiment of a data cable showing my new design;

FIG. 10 is a second perspective view thereof;

FIG. 11 is a front view thereof;

FIG. 12 is a back view thereof;

FIG. 13 is a left side view thereof;

FIG. 14 is a right side view thereof;

FIG. 15 is a top view thereof; and,

FIG. 16 is a bottom view thereof.

The data cable is seen with a break in its length. These broken line breaks and any matter between the breaks form no part of the claimed design. The broken lines showing the internal structure of the connector features on each end of the data cable depict unclaimed portions of the data cable and form no part of the claimed design.
